UNITED STATES PATENT OFFICE.

JOHN COLLINS AND ALFRED SHEPEARD, OF HANCOCK, NEW YORK.

RAILWAY-TIE PLATE AND SPIKE.

1,209,396.

Specification of Letters Patent. Patented Dec. 19, 1916.

Application filed May 9, 1916. Serial No. 96,357.

To all whom it may concern:

Be it known that we, JOHN COLLINS and ALFRED SHEPEARD, citizens of the United States, residing at Hancock, in the county of Delaware and State of New York, have invented certain new and useful Improvements in Railway-Tie Plates and Spikes; and we do hereby declare the following to be a full, clear, and exact description of the invention, such as will enable others skilled in the art to which it appertains to make and use the same.

This invention relates to a railroad spike and a tie plate, and the primary object of the invention is to provide a construction including a railroad spike and a tie plate which will prevent the creeping or lateral spreading of the rails of a railway track.

Another object of this invention is to provide a key for engagement with the spikes for locking them for preventing them from accidentally working loose or being drawn until the key is removed.

With the foregoing and other objects in view this invention consists in such novel features of construction, combination and arrangement of parts as will be hereinafter more fully described, illustrated in the accompanying drawing and claimed.

In describing the invention in detail reference will be had to the accompanying drawing wherein like characters designate like and corresponding parts throughout the several views, and in which:

Figure 1 is an end view of the improved tie or spiking plate secured to a tie. Fig. 2 is a longitudinal section through the plate showing the spike in side elevation. Fig. 3 is a cross section through the plate and a portion of a tie. Fig. 4 is an inverted perspective of the plate, and Fig. 5 is a perspective view of the key employed for locking the spike against accidental drawing.

Referring more particularly to the drawing, 1 designates an ordinary T-rail and 2 the ordinary type of cross tie. The spiking plate generically indicated by the numeral 5, rests upon the upper surface of the tie 2 and is provided with a plurality of pyramidal lugs 6 which extend downwardly from its under surface, and are embedded in the upper surface of the tie for preventing creeping of the plate 5 with respect to the tie 2. The plate 5 is provided with a plurality of openings which are arranged in pairs as indicated at 7. The end 8 of the

plate is thicker than the remainder of the plate, which provides a shoulder 9 against which one edge of the base of the T-rail 1 abuts. The openings 7 are provided for receiving the shanks 10 and 11 of the railway spike 12. Each of the spikes comprises a relatively long shank 10 and the relatively short shank 11, and the head 13. The shanks 10 and 11 are positioned in alignment with each other. The long shank 10 of the spike 12 is positioned inwardly or next to the base of the T-rail 1, while the short shank 11 is positioned outwardly, and is provided for preventing the tilting or oscillatory movement of the spike under movement of the T-rail 1. The plate 5 has upstanding lugs 14 formed thereon which engage the base of the T-rail.

The plate 5 is provided with a key way 15 formed in its under surface which key way communicates with one edge of the plate and with a pair of the openings 7. A key 16 is provided for insertion in the key way 15, and in a notch or recess 17 which is formed in the short shank 11 of one of the spikes 12. This key 16 prevents the working loose of the spike structure 13 and also will prevent the withdrawing of the spike, until after the key has been removed from the key way. The key 16 is provided with a head 18 which projects outwardly from the edge of the plate 5 so as to facilitate the withdrawal of the key.

If it is so desired, keys may be employed in connection with all of the spikes in lieu of any one of them without departing from the spirit of this invention.

In reducing the invention to practice, certain minor features of construction combination and arrangement of parts may necessitate alterations to which the patentee is entitled provided such alterations are comprehended within the scope of what is claimed.

What is claimed is:

1. In a device as set forth, the combination, of a spiking plate having a pair of openings therein, a spike, a relatively long and a relatively short shank formed upon said spike, said shanks adapted for insertion through said openings, said plate being provided with a key way formed in its under surface, a key for insertion in said key way, said short spike shank provided with a notch for receiving one edge of said key for locking said spike against accidental movement.

2. In combination, a spiking plate adapted for resting upon the upper surface of a railway tie, a plurality of substantially pyramidal lugs formed upon the under surface of said plate and adapted for embedding in said tie, said plate being provided with a plurality of openings arranged in pairs, railway spikes, each of said spikes provided with a long shank and a short shank, said shanks adapted for insertion through the pairs of openings for locking said plate in engagement with a tie and for holding an ordinary T-rail thereon.
3. In combination, a spiking plate adapted for resting upon the upper surface of a railway tie, a plurality of substantially pyramidal lugs formed upon the under surface of said plate and adapted for embedding in said tie, said plate being provided with a plurality of openings arranged in pairs, railway spikes, each of said spikes provided with a long shank and a short shank, said shanks adapted for insertion through the pairs of openings for locking said plate in engagement with a tie and for holding an ordinary T-rail thereon, said plate having a shoulder formed thereon adapted for abutment with one edge of the base of a T-rail, said plate having a key way formed in its under surface, a key for insertion in said key way, the short shank of said spike provided with a notch for receiving a portion of said key for locking the spikes against accidental withdrawal.
4. In combination, a spiking plate adapted for resting upon the upper surface of a railway tie, a plurality of substantially pyramidal lugs formed upon the under surface of said plate and adapted for embedding in said tie, said plate being provided with a plurality of openings arranged in pairs, railway spikes, each of said spikes provided with a long shank and a short shank, said shanks adapted for insertion through the pairs of openings for locking said plate in engagement with a tie and for holding an ordinary T-rail thereon, said plate having a shoulder formed thereon adapted for abutment with one edge of the base of a T-rail, said plate having a key way formed in its under surface, a key for insertion in said key way, the short shank of said spike provided with a notch for receiving a portion of said key for locking the spikes against accidental withdrawal.

In testimony whereof we affix our signatures in presence of two witnesses.

JOHN COLLINS.
ALFRED SHEPEARD.
